UNITED STATES PATENT OFFICE.

MAX E. SCHENKE, OF JERSEY CITY, NEW JERSEY.

DESIGN FOR A VANITY CASE.

Application filed June 19, 1928. Serial No. 27,200. Term of patent 3½ years.

To all whom it may concern:

Be it known that I, MAX E. SCHENKE, a citizen of the United States, residing at Jersey City, in the county of Hudson and State of New Jersey, have invented a new, original, and ornamental Design for Vanity Case, of which the following is a specification, reference being had to the accompanying drawing, forming part thereof.

The figure is a perspective view of the vanity case showing my new design.

I claim:

The ornamental design for a vanity case as shown.

MAX E. SCHENKE.
